UNITED STATES PATENT OFFICE.

JOHN V. PATTEN, OF CHICAGO, ILLINOIS, ASSIGNOR TO HERO FURNACE COMPANY, OF CHICAGO, ILLINOIS, A CORPORATION OF ILLINOIS.

AIR-WASHER HUMIDIFIER FOR FURNACES.

Application filed June 20, 1921. Serial No. 478,847.

To all whom it may concern:

Be it known that I, JOHN V. PATTEN, a citizen of the United States, residing at Chicago, in the county of Cook and State of Illinois, have invented certain new and useful Improvements in Air-Washer Humidifiers for Furnaces, of which the following is a specification.

This invention relates to means for suitably disposing a water supply to wash and saturate the air which is distributed by hot air furnaces, and while it is particularly designed for that class of furnaces which are known in the trade as "pipeless furnaces" it may be used with any other kind of furnaces to which it is or may be conveniently adapted.

The object of the invention is to provide means of simple character for holding a supply of water in sufficient quantity and in an advantageous position to thoroughly wash and saturate the air during its passage through the furnace so that it will be delivered in a clean and properly saturated condition and thus avoid the dust and dryness common to hot air furnaces.

A further object of the invention is to provide a plurality of communicating pans for holding the water supply, these pans being of a size and shape which will permit them to be easily removed from the furnace for cleaning, and as easily replaced.

And further objects are to provide simple means for filling the pans and means for indicating the depth of water in the pans.

In the accompanying drawing illustrating a selected embodiment of the invention—

Fig. 1 is a perspective view of a pipeless furnace, partly broken away, and in section, showing my invention embodied therein;

Fig. 2 is a rear perspective view of the furnace with the jackets or shells removed;

Fig. 3 is a detail sectional view on the line 3—3 of Fig. 1 showing the indicating means.

Referring to the drawing, the furnace is designated generally 4 and it comprises an outer jacket or shell 5 supported on a base 6, and an inner jacket 7 supported on arms or brackets 8, the two jackets being spaced apart to provide an air passage 9, and the arms 8 being located to support the inner jacket 7 at a distance above the base so that air passing down through the passage

9 may pass under the lower edge of the inner jacket 7 and thence up between said inner jacket and the body of the furnace in the usual manner. At the sides of the front of the furnace there are end posts or supports 10, 10' which may be made of channel iron or a Z-bar to which the ends of the jackets are secured.

I provide a plurality of pans 11, 12, 13, which are arranged in juxtaposition within the outer jacket and decrease in depth progressively in the order named. The pan 11 is provided at its discharge end with a downwardly and outwardly inclined flange 11' overlapping the adjacent edge of the pan 12 and the latter is similarly provided with a flange 12' which overlaps an adjacent edge of the pan 13, so that water may over-flow from the pan 11 to the pan 12 and from the pan 12 to the pan 13. A pipe 14 is supported in one of the supports, as 10', and it is provided at its outer end with an inlet 15 into which the water is poured to flow through the pipe 14 into the pan 11. The indicating means for determining the level of the water in the pan 13 comprises a float 16 connected with a lever 17 which is pivoted at 18 on the support 10, and one end of this lever projects through an opening 19 in said support and is provided with a pointer 20 which indicates the level of the water in the pan 13 by its position relative to suitable marks on the support. A guard 21 carried by a bracket 22 suitably secured to the support 10 is provided with a flared lower end 21' to keep the float in proper operative position.

It will thus be seen that by very simple means I am able to maintain a sufficient supply of water in the bottom of the furnace to thoroughly wash and saturate the inflowing air in its passage to the heating chamber 23 and before it is discharged from the furnace. The water pans are located at the bottom of the passage 9 from one support 10 to the other 10' so that all of the air is thoroughly cleaned and saturated. In actual practice it has been found that the pans will collect a considerable quantity of dirt in a comparatively short time and for this reason it is desirable to have a plurality of pans which can be easily removed from the furnace and as easily re-arranged in place in proper relation to each other and so that

one will over-flow into the other, this construction being desirable in order that the pans may be removed through the door which is usually located in the side of the outer jacket. This door can be arranged in any suitable position and two or more doors may be provided, if found desirable, to facilitate removal of the pans for cleaning and replacement thereof in the furnace.

10 My invention is simple in construction, it can be easily applied to furnaces already installed, it can be made and installed at low cost and it enables an ample and sufficient supply of water to be maintained where it will not only wash and clean the air but also saturate it to a degree of humidity which is most desirable in hot air heated homes.

I am aware that changes in the form and in the proportion and arrangement of parts 20 may be made without departing from the spirit or sacrificing the advantages of my invention and I reserve the right to make all such changes as fairly fall within the scope of the following claims:

25 I claim:

1. In a hot air furnace, the combination of a base, a fire box supported thereon, an outer shell rising from the base, an inner jacket between the shell and the fire box and 30 having its bottom terminated above the base to provide a communication between the down draft air space between the jacket and the shell and the up draft air space between the jacket and the fire box, a plurality of re-

movable open topped water pans supported 35 on the base and extending around the fire box, successive pans having a detachable overflow connection disposed entirely within the furnace, a water supply pipe leading inwardly through the shell and communicating with one of the pans, and a float actuated indicator for indicating the level of the water in the pans.

2. In a hot air furnace, the combination of 40 a base, a fire box supported thereon, an outer shell rising from the base, an inner jacket between the shell and the fire box and having its bottom terminated above the base to provide a communication between the down draft air space between the jacket and the shell and the up draft air space 45 between the jacket and the fire box, a plurality of removable open topped water pans supported on the base and extending around the fire box, successive pans having a detachable overflow connection consisting of a 50 downwardly and outwardly inclined flange at the discharge end of one of the pans and overlapping the adjacent edge of the next successive pan, a water supply pipe extending inwardly through the outer shell and communicating with one of the terminal pans, a float within the opposite terminal pan, and a water level indicator associated 55 with the float and extending outwardly through an opening in the shell.

JOHN V. PATTEN.
